UNITED STATES PATENT OFFICE.

RICHARD W. HUBBARD, OF ASHTABULA, OHIO.

HINGE.

Application filed August 17, 1922. Serial No. 582,427.

To all whom it may concern:

Be it known that I, RICHARD W. HUBBARD, a citizen of the United States, residing at Ashtabula, in the county of Ashtabula and

5 State of Ohio, have invented new and useful Improvements in Hinges, of which the following is a specification.

My present invention pertains to concealed door hinges and it contemplates the provision of a concealed hinge that is so constructed and arranged with respect to a door and jamb that the hinge is instantly detachable with respect to its complementary hinge member.

10 15 The invention further contemplates the provision of a hinge that in addition to its detachable characteristics is also adapted to permit of the hanging of a door with respect to a jamb without the employment of skilled

20 labor.

The invention further contemplates the provision of a concealed hinge by which the elimination of the well known pintle is effected.

25 30 The invention in all of its details will be fully understood from the following description and claims when the same are read in connection with the drawings accompanying and forming part of this specification, in which

Figure 1 is a front elevation illustrating my novel hinge as the same appears when properly secured to a door and jamb.

35 Figure 2 is a transverse sectional view showing the door and jamb as well as the plates of the hinge and the concealed connection as the same appear when the door is closed.

40 Figure 3 is a similar view showing the door partially open.

Figure 4 is a view illustrating the hinge or portion as secured to a door.

Figure 5 is a view showing another portion of the hinge secured to the jamb.

45 Figure 6 is a view showing a portion of the door and the manner in which the same is cut away to receive the door hinge portion.

50 Figure 7 is a view illustrating one portion of the hinge in detail.

Similar numerals of reference designate corresponding parts in all the views of the drawings.

55 For the purpose of illustration, I have indicated the door by the numeral 2 and the jamb by the numeral 1 but it will be mani-

fest from the future description of the invention that the plates and elements may be used with equal facility either on the door or on the jamb.

60 The door 2 as well as the jamb 1 are provided with plates; the plate of the jamb being indicated by 8 and having the rolled outwardly extending portion 10 that terminates in the face portion 11 that bears against the outer flange of the door and the said plate 8 is adapted to seat in a channel or kerf formed in the edge of the jamb and indicated by 3. This plate 11 is provided with apertures 11' for the reception of fastening

65 screws when deemed expedient and the said plate is further provided with the rivet headed screws 13 that extend a slight distance away from the face of the plate for an important purpose hereinafter set forth.

70 75 The screws 13 under normal conditions are sufficient to detain the plate in proper position on the jamb and the apertures 11' are merely provided for the purpose of reception of holding screws where the liability of

80 the door and jamb being subjected to undue strain is apparent. In order to secure the plate in proper position on the jamb prior to the permanent fastening of the plate to the jamb I provide on the sides and ends of

85 the plate small apertures through which small nails (not numbered) pass to initially hold and set the plate in proper position. The door 2 is provided with a plate

90 95 similar to the plate 8 with the exception that it has a cut out portion in one edge. The door is provided with the cut away circular portion 16 and the plate 4 is provided with a face 7 that is secured to the door by means of the screws 7'.

This plate is further provided with a rounded portion 6 that corresponds to the portion 10 of the plate A.

100 The movable element of my novel hinge comprises the leaf 12 having the peculiarly constructed slots 12' and the said leaf is further provided with a strap of semi-circular construction and indicated by 14 and having the portion 17 that terminates in the pintle receiving element which in turn registers with the pintle receiving elements of the leaf 15'. This leaf is somewhat similar to the leaf 12 with the exception that it is

105 not provided with the slots but is provided with screws receiving apertures adapted to receive the screw or screws 7'. The leaves 12 and 15' are securely held with respect to each other by means of the pintle 18 and

the leaf 15^b is provided with an opening 15^a through which the strap 14 passes into the cut out portion 16 of the door. The leaf is further provided with the integral portion 15 that bears against the side of the door as shown in Figure 4.

In the practical use of this invention the plates 4 and 8 are properly positioned by means of the small nails but previous to this securing operation the movable element comprising the leaves 12 and 15^b is positioned on the plate 4 with the portion 7 resting between said leaves. The leaves are then separated to the position shown in Figure 3 and the screws 7^a are then seated into the door. Manifestly if desired screws may be passed through some of the apertures of the leaf 15^b before the plate and portion 7 thereof has been placed so as to be straddled by the leaves. When the plate has been properly positioned on the door as shown in Figure 4 it is then merely necessary to secure the plate 8 to the jamb by means of the small brads or pins 5. The rivet headed screws are then driven so as to have the head extending slightly outward from the plate when it is simply necessary to lift the door so that the channels 12^a may clear the rivets 13. When this has been accomplished it is simply necessary to let go the door in order that the upper ends of the channels may bear against the shank of the screw. It will be apparent that brads 9 may be used to properly position the plate 8 as is the case with the position of the plate 4 by means of the brads 5. It will be readily apparent that a novice may hang the door and the hinge as a whole as far as the application thereof is practically fool proof for the reason that because of a peculiar construction of the slots or channels 12^a the leaves 12 and 15^b may be put on upside down or vice versa without defeating the purpose of the invention.

The invention pertains to the hanging of doors for houses, vehicles and the like and more particularly to automobile doors. The hanging of the latter class of doors requires the exercise of a large amount of skill with the consequent increase in the cost of the vehicle due to the high wages paid to skilled mechanics. With my invention, any person capable of handling a screw driver may within a very short time become efficient in the attachment and securing of a door to a jamb and when so attached by means of my invention the liability of the sagging of a door is effectually precluded. The removal of a door from the jamb or casing is a very simple matter and this is highly advantageous when it is stated that

frequently a motorist or the like desires to increase the carrying capacity of the vehicle by removing the door from the jamb which could not be attempted with hinges at present in use on motor vehicles.

It will also be apparent that the person applying the hinge is not required to exercise skill in the selection of the element to be secured to the door or jamb as the said elements may be used with equal facility either on the door or on the jamb.

The hinge is instantly detachable and is likewise a right-hand or left-hand hinge and permits of the removal of the door without the withdrawal of the screws.

When desired the leaves 12 and 15^b may be constructed without the strap 14 and in such case it would be necessary to hinge the plates to each other by means of a pintle surrounded by a spring. This construction would permit of the hanging of light doors such as screen doors.

Having described my invention what I claim and desire to secure by Letters Pat-⁸⁵ ent is:

1. In a door hinge, comprising two plates, one of which is adapted to be secured to a door casing and the other of which is adapted to be secured to a door; said plates being connected in hinged manner with respect to each other and having a strap formed integral on one of the plates and extending and surrounding one face of the opposing plate, finishing plates secured on the abutting surfaces of the casing and door, projections formed on one of the finishing plates for engaging elongated slots of the hinged plates and a slot formed in the opposing finishing plate to permit travel of the strap of the hinged plates into a cut out portion of the door casing.

2. A door hinge comprising two plates, a slot formed in one plate, a strap formed integral on one plate and extending through the slot of the first plate whereby the plates are hinged to each other; said strap surrounding one of the plates, finishing plates secured on the door faces, projections formed on one finishing plate to engage slots formed in the opposite plate, and a cut-out portion arranged in rear of one plate to permit travel of the strap on operation of the door.

In testimony whereof I have hereunto set my hand in presence of two subscribing witnesses.

RICHARD W. HUBBARD.
